UNITED STATES PATENT OFFICE

HARRY H. BATES AND FOLGER ADAM, OF JOLIET, ILLINOIS.

ELECTROLYTIC PROCESS.

1,023,545.

Specification of Letters Patent.

Patented Apr. 16, 1912.

Application filed June 12, 1911. Serial No. 632,657.

To all whom it may concern:

Be it known that we, HARRY H. BATES and FOLGER ADAM, citizens of the United States, residing at Joliet, in the county of Will and State of Illinois, have invented a certain new and useful Electrolytic Process, of which the following is a specification.

This invention relates to a new and useful process for electrolytically treating certain chemicals, and particularly to such a process as carried on continuously so that the mother liquor flows continuously through a circuit or through a portion of a circuit, so that the mother liquor can be used over and over again.

The invention relates particularly to the production of chlorates from the chlorids of alkaline or alkaline earth metals.

In carrying on the process to which our invention relates, an electrolytic cell of any desired form is used for bringing about certain reactions in the chemicals. Thus, in the particular process to which our invention relates the electrolytic cell serves to convert the chlorids into the chlorates. It has been found by past experience that such a converting process may be carried on continuously by introducing new liquor into one portion of the electrolytic cell and without drawing the treated liquor from another portion of the cell, provided the proper conditions are maintained within the cell and within the several portions of the necessary apparatus as to temperature, density of current, voltage, etc. Thus, for example, if the temperature of the liquor within the cell is too low, the electrolytic conversion will not take place, or, if at all, it will not result in the production of the proper and desired products. In other words, temperature within the cell is an important condition and must be maintained at the proper point if satisfactory results are to be secured.

After the treated liquor passes away from the electrolytic cell, it must generally be cooled, in order to insure precipitation of the proper crystals. Therefore, it is a general proposition that where a continuous circuit of liquor flow is maintained the liquor must be heated again before it enters the cell, or else means must be provided for heating it to the necessary point within the cell. The electric current flowing through the cell heats the liquor therein to an extent depending largely upon the voltage or quantity of the current, so that the

amount of heating within the cell may be determined to a certain extent by adjusting the voltage or the quantity of the current. Now it is a general proposition that a certain minimum voltage must be maintained within the cell in order to insure conversion of the chlorids into the chlorates, and any voltage less than this amount will not insure such conversion. On the other hand, the amount of heating of the liquor which results from this amount of voltage is, as a general rule, comparatively small and not sufficient to raise the temperature of the liquor to that minimum temperature which it should have in order to insure satisfactory operation. Therefore, if the comparatively cool liquor is to be heated by means of the current within the cell, to the proper point, then the quantity and voltage of the current must be in excess of that which is necessary to carry on the electrolytic conversion, and such excess quantity and voltage of current results in a dead loss of electric energy. On the other hand, in carrying on the electrolytic process to which our invention relates, we make use of the heat which would otherwise be wasted in the liquor as it leaves the electrolytic cell, because such liquor must be cooled and give off a certain amount of heat before the proper precipitation of the chlorates will take place. Therefore, we use this excess heat, which is carried away from the electrolytic cell, for the purpose of preheating the liquor before it enters the cell, and thus we are enabled to provide a process wherein the liquor enters the cell at a temperature such that no excess quantity or voltage of the electric current within the cell is necessary to raise the liquor therein to the proper temperature and maintain it at such temperature. Therefore, our process is one in which the temperature of the liquor within the cell is not determined by the current therein, but, on the other hand, is determined by the entering temperature or the amount of preheating. Also, it is a process in which a large saving of electrical energy is made, and therefore a process which can be carried on much cheaper than any other with which we are familiar. At the same time that we make use of the heat which is carried away from the cell by the electrolyte, we are enabled to regulate the amount of preheating which will take place by regulating the time during which the in-

coming liquor will be exposed to the heat of the outgoing liquor. By this means we are enabled to perfectly adjust the temperature of the incoming liquor and therefore to insure the most perfect operation of the conversion process.

A further advantage which accrues from our process is this: that where the liquor must be heated solely by the current within 10 the cell such current must be of excess quantity and voltage, as has been heretofore pointed out. Now this excess quantity and voltage of current tends to deteriorate the quality of the resulting product, so that the 15 product is not so perfect as is the product resulting from our process, in which no excess quantity or voltage of current is required.

In the drawing we have shown in outline 20 a simple form of mechanism for carrying on our improved process. It will be understood that this drawing illustrates only one of a large number of possible arrangements, any one of which would still incorporate the 25 gist of our invention.

In the drawing, the electrolytic cell is designated by the numeral 1. We are not here concerned with its exact construction and characteristics, beyond the fact that it 30 should be an electrolytic cell designed and intended for the so-called continuous operation.

The electric wires for the cell are designated by the numerals 2 and 3. The liquor 35 enters at the top of the cell through a funnel-shaped opening 4 and leaves the bottom of the cell through a pipe 5. A resaturating tank 6 is provided in which new chlorids are added to the mother liquor so that the 40 mother liquor will be properly saturated when it again reaches the cell. From the tank the liquor flows down through a pipe 7 and passes through a coil 8, which is submerged within liquor contained in a pre-heating receptacle 9. From the coil the liquor passes up through a pipe 10 and finally discharges through the opening 11 thereof into the funnel 4. As the treated liquor passes out through the pipe 5, it 45 gains access to the preheating receptacle 9 and therefore surrounds the coil 8 through which the incoming liquor is passing. By this means the excess heat of the outgoing liquor serves to preheat the incoming liquor 50 and, as before stated, the excess or waste heat is thus economically used and at the same time permits us to operate the electrolytic cell without the necessity of passing an excess quantity and voltage of current 55 through the same.

A spout 12 is attached to the preheating receptacle 9. This spout may be raised and lowered as indicated by dotted lines in the figure, so that the height at which the liquor 60 stands within the preheating receptacle may

be accurately determined by merely raising or lowering the spout the necessary amount. Obviously, the higher the spout is raised the higher the outflowing liquor will stand as it surrounds the coil 8, and therefore the 70 incoming liquor within the coil 8 will be pre-heated to a greater or less extent, depending upon whether the spout be raised or lowered. By this means we are enabled to accurately adjust the amount of preheating, such pre-heating, nevertheless, always being occasioned by the excess heat of the outflowing liquor.

Sometimes the liquor as it flows out through the spout will have been sufficiently 80 cooled by the liquor within the coil 8 so that it will be practically ready to precipitate its crystals. When this is the case, the outflowing liquor which leaves the spout 12 may be passed immediately to a precipitating receptacle. On the other hand, at times the liquor may not be quite cool enough to precipitate its crystals in a satisfactory manner. In such a case, a still further cooling should be effected, and for this reason 90 we provide a cooling or condensing receptacle 13 into which the treated liquor may flow through a pipe 14. A funnel 15 on the pipe 14 receives the liquor directly from the spout. A cooling coil 16 is contained within the receptacle 13 and through it may be passed any suitable cooling medium, such as cold water. A pipe 17 carries the cooled and condensed liquor from which the crystals have been removed, in the receptacle 18, 100 up to the tank 6, any suitable form of pump 18 serving to effect a continuous movement or flow of the liquor. Valves 19 and 20 may be provided in the pipes 7 and 10 respectively, for starting and stopping the flow of 105 liquor.

While we have stated that in general our process is one intended for the treatment of chlorids for the production of chlorates therefrom, still we do not limit our process 110 to the treatment of such chemicals, for it is evident that there may be large numbers of chemicals which may be thus treated in the manner herein set forth. We desire, however, to particularly point out the fact that 115 our process is one in which the temperature of the liquor within the cell is determined, not by regulating the quantity and voltage of such current but, on the other hand, by regulating the temperature at which the 120 liquor enters the cell. Further, we desire to point out that the heat which preheats the liquor is derived from the outflowing liquor itself, and that therefore a certain conservation of the energy is effected, so that there 125 exists a certain total amount of heat energy within the cell and adjoining portions of the circuit, this energy being restored to the cell continuously as rapidly as it is removed from the same. And for this reason there 130

will arise times when it is not at all necessary to use the condensing receptacle 13, which we have illustrated, however, for the purpose of showing that such a condensing 5 receptacle may be used should that become necessary.

Although in the construction shown and previously described herein the heat which is used for preheating the liquor is derived 10 from the liquor as the same emerges from the electrolytic cell, still we do not limit ourselves to such an arrangement, as we contemplate within the scope of our invention any arrangement in which the liquor is pre- 15 heated to the necessary extent before it enters the cell, such an arrangement being used in conjunction with a system which makes use of a continuous flow of the liquor.

We claim:

20 1. The electrolytic process which consists in passing a flowing stream of liquor through a preheater and then through an electrolytic cell, and conducting the emerging stream of liquor containing heat into 25 the preheater, the inflowing liquor being under the heating influence of the outflowing liquor just that interval of time necessary to raise the temperature of the inflowing liquor to the proper point for electrolytic dissociation within the electrolytic cell, 30 and the voltage within the cell being just sufficient to effect dissociation of the liquor within the same, substantially as described.

2. The electrolytic process which consists 35 in passing a stream of liquor through a pre-heater and then through an electrolytic cell, and conducting the emerging hot liquor from the cell into the preheater to preheat the incoming liquor, the stream of incoming 40 liquor being under the heating influence of the outflowing liquor just the necessary length of time, corresponding to the magnitude of said stream of inflowing liquor, to heat said inflowing liquor to the desired 45 point for entrance into the electrolytic cell, substantially as described.

3. The electrolytic process which consists in passing a continuously flowing stream of liquor through a preheater and then through an electrolytic cell, and conducting the outflowing liquor from the cell containing an excess of heat to the preheater and bringing it into heating association with the inflowing liquor, whereby the temperature of the stream of inflowing liquor is raised to just 50 that point desirable for entrance into the electrolytic cell, and whereby the stream of outflowing liquor is cooled to assist in precipitating its crystals, substantially as described. 55

60 4. The electrolytic process which consists in passing a continuously flowing stream of liquor through a preheater and then into an electrolytic cell, and conducting the outflowing liquor into the preheater and adjusting 65 the time during which the outflowing liquor is in heating association with the stream of inflowing liquor to such a point that the inflowing liquor is preheated the desired amount, substantially as described. 70

5. The electrolytic process which consists in passing a continuously flowing stream of liquor through a pre-heater and then into an electrolytic cell, and adjusting the temperature of the inflowing liquor by regulating 75 the amount of pre-heat, substantially as described.

6. The electrolytic process which consists in passing a continuously flowing stream of liquor through a pre-heater and then 80 through an electrolytic cell, and adjusting the temperature of the liquor as it enters the cell by the amount of pre-heat to that point necessary to give the desired electrolytic action within the cell, substantially as described. 85
